UNITED STATES PATENT OFFICE.

GUSTAV H. GENTZEL, OF JERSEY CITY, NEW JERSEY, ASSIGNOR TO THE
JOHN MEHL & COMPANY, OF SAME PLACE.

APPAREL-BELT.

SPECIFICATION forming part of Letters Patent No. 659,022, dated October 2, 1900.

Application filed June 21, 1900. Serial No. 21,048. (No model.)

To all whom it may concern:

Be it known that I, GUSTAV H. GENTZEL, a citizen of the United States, and a resident of Jersey City, in the county of Hudson and State of New Jersey, have invented new and useful Improvements in Apparel - Belts, of which the following is a specification.

My invention relates to certain improvements in apparel-belts, and has for one object to provide a belt with a new and improved device for detachably connecting the belt with a button on the waistband of a skirt or other article of apparel, the said device and belt being immovably together at one point and having a sliding connection with each other at another point, so as to permit the ready attachment and removal of the button and so as not to interfere in any respect with the set of the belt when engaged with the button.

A further object is to provide a very cheap and simple construction and one which will successfully withstand great strains, to which supporting-belts of this character are subjected.

A practical embodiment of my invention is represented in the accompanying drawings, in which—

Figure 1 represents a perspective view of a belt with my improved waist-button - attaching device applied thereto. Fig. 2 is an enlarged longitudinal section through a portion of the belt and the attaching device, taken in the plane of the line 2-2 of Fig. 1; and Fig. 3 is a similar view to Fig. 2, showing the manner of buckling the belt outwardly away from the attaching device by sliding the loose connection between the belt and the device inwardly toward the fixed connection for facilitating the insertion of the waist-button.

The belt is denoted as a whole by A, and it may be of any suitable style, shape, and material. A pair of cross-straps a a' are secured to the inside of the belt at the back thereof, these cross-straps being preferably secured to the belt at their opposite ends only.

The attaching device is shown as comprising a flexible strip or plate B, of metal or other suitable material, and it is provided with an elongated slot b, extending length-

wise therein for receiving the shank of a waist-button. (Not shown herein.) This device B is further provided with a button-receiving opening b', communicating with the slot at 55 one end thereof, the said opening b' being of a size sufficient to permit the ready insertion of a button therethrough without bending or displacing any portion of the device. One end of the device is permanently secured to 60 the cross-strap a of the belt by means of a rivet b², which passes through the plate and the cross-strap. The belt and the other end of the attaching device have a sliding connection with each other by loosely connecting 65 the device to the cross-strap a' by means of a rivet b³, which passes through the slot b, near one end thereof, and also through the said cross-strap a'. The button - receiving opening b' may communicate with the slot at 70 other points along its length than that shown, if so desired.

By the use of the device hereinabove described, which is provided with a button-shank receiving elongated slot and a button-receiving opening communicating therewith, I am enabled to readily insert and remove the waist-button without spreading the device.

Because of the limited sliding connection between one part of the device and the belt 80 while the other part of the device is secured firmly against movement with respect to the belt I am enabled to produce quite a bend in the belt at the back of the device by sliding the loose connection between the belt and the 85 device inwardly along the slot b' for still further facilitating the insertion and removal of the button. When the button has been inserted into its position between the device and the back of the belt, the belt may be 90 drawn snugly around the body of the wearer and will preserve its shape even at the point of attachment of the button thereto.

It is evident that changes might be resorted to in the form and arrangement of 95 the several parts without departing from the spirit and scope of my invention. Hence I do not wish to limit myself strictly to the structure herein set forth; but

What I claim is—

1. The combination with a belt, of a waist-button-attaching device located along the in-

side of the belt, the said belt and attaching device being secured immovably together at one point and having a sliding connection with each other at another point, substantially as set forth.

2. The combination with a belt having a pair of cross-straps spaced apart and secured thereto, of a waist-button-attaching device having one end secured rigidly to one 10 of the cross-straps and having its other end loosely secured to the other cross-strap, substantially as set forth.

3. The combination with a belt, of a waist-button-attaching device located along the in- 15 side of the belt, comprising a flat strip of flexible material having an elongated button-receiving slot therein and a button-receiving opening communicating with the said slot, the said belt and attaching device being secured

immovably together at one point and having 20 a sliding connection with each other at another point, substantially as set forth.

4. The combination with a belt, of a waist-button-attaching device having a button-shank receiving elongated slot therein and a 25 button-receiving opening communicating with the said slot, of rivets for securing the device to the belt, one of the said rivets passing through the said elongated slot in the device, substantially as set forth. 30

In testimony that I claim the foregoing as my invention I have signed my name, in presence of two witnesses, this 15th day of June, 1900.

GUSTAV H. GENTZEL.
